(57) **CLAIM**

The ornamental design for a display screen of a computing device with a graphical user interface, as shown and described.

DESCRIPTION

FIG. 1 is a front view of a first image of a first embodiment of a display screen of a computing device with a graphical user interface;

FIG. 2 is a second image thereof;

FIG. 3 is a third image thereof;

FIG. 4 is a front view of a first image of a second embodiment of a display screen of a computing device with a graphical user interface;

FIG. 5 is a second image thereof; and,

FIG. 6 is a third image thereof.

The appearance of the graphical user interface sequentially transitions between the views shown in FIGS. 1-3. The appearance of the graphical user interface sequentially transitions between the views shown in FIGS. 4-6. The process or the period in which the appearance of the graphical user interface transitions to another appearance of the graphical user interface forms no part of the claimed design.

The outer perimeter broken line shows a display screen and forms no part of the claimed design. All broken line texts form no part of the claimed design. All other broken lines show portions of the graphical user interface that form no part of the claimed design. Shading shown within solid outlines indicates a contrast in appearance.
